(57) **CLAIM**

The ornamental design for an on-board tool box for portable wire feeder, as shown and described.

DESCRIPTION

FIG. 1 is a top perspective view of an on-board tool box for portable wire feeder showing my new design with environment shown in broken lines;

FIG. 2 is a bottom perspective view thereof;

FIG. 3 is a front view thereof;

FIG. 4 is a rear side view thereof;

FIG. 5 is a left side view thereof;

FIG. 6 is a right view thereof;

FIG. 7 is a top view thereof; and

FIG. 8 is a bottom view thereof.

FIG. 9 is a perspective view of the tool box in a closed position; and,

FIG. 10 is a perspective view of the tool box in an open position.

The broken lines shown are environmental only and form no part of the claimed design.
